MATCH COMB HANDLING CONVEYER

Rodney S. Pullen, Akron, Ohio, assignor to Pullen-lite Company, Philadelphia, Pa., a corporation of Pennsylvania

Application July 1, 1943, Serial No. 493,117

12 Claims. (Cl. 144—51)

1

My invention relates to mechanism for handling match combs from a hopper, in which the full combs are stored, intermediately, to a conveyor by which the separated book match comb sections are fed to other mechanism.

One of the purposes of the invention is to cut and separate match comb sections, spacing them and feeding them to conveyor gripping mechanism.

A further purpose is to provide cutting mechanism for separating match combs into match sections, mechanism for feeding the match sections and guiding and diverting mechanism by which the sections are separated and properly spaced for ultimate engagement in groups by a second conveyor which supports them during other operations.

A further purpose is to cut match combs up into sections suitable for match packets, to feed the combs step by step by conveyor flights which transfer them one step at a time, and in which the conveyor flights withdraw from engagement with the sections, retracting lengthwise of the conveyor to the rear of the following sections, re-engage but with different sections and again convey one step and withdraw from engagement.

Further purposes appear in the specification and in the claims.

Figure 1 is a top plan view of a hopper containing match combs, and of fragmentary mechanism for feeding the combs. Further mechanism is shown in Figure 3.

Figure 2 is a section of Figure 1 taken upon line 2—2 and looking in the direction of the arrow.

Figure 2a is a section upon line 2a—2a of Figure 2.

Figure 2b is a section upon line 2b—2b of Figure 2a.

Figure 3 is a fragmentary top plan view of a further portion of the mechanism seen in Figure 1, showing mechanism operating concurrently with the operation of the parts in Figure 1 but upon stock which already has been acted upon by the structure of Figure 1.

Figure 4 is a vertical section parallel to the direction of match movement, taken on the line 4—4 of Figure 3, showing operating mechanism for cutting the match combs and conveying the match comb sections.

Figure 4a is a fragmentary top plan view of a part of Figure 4.

Figure 5 is a section of the mechanism seen in Figure 3 taken upon line 5—5.

2

Figure 6 is a diagrammatic view of driving connections for the plunger and flipper operation.

Figure 6a is a fragmentary cross-section showing the plunger of Figure 6.

Figure 6b is a fragmentary perspective of part of the plunger of Figure 6.

In the drawings similar numerals indicate like parts.

In the making of match packets the well-known match combs are cut into match comb sections, each of which provides the matches for one packet. Initially the matches for a section are attached at their stick ends to stubs and are handled by the stubs.

15 My present invention is directed to the handling of match combs to cut them up into sections, to separate the sections a distance so that they can be operated upon, and to mount the sections so spaced by supporting the stubs of the 20 sections upon a conveyor chain for handling at other points during the making of the packets. Though I indicate a four packet comb and show mechanism adapted to such a comb, it is my intention to deal with, cut separate and mount 25 combs of whatever length, whatever the number of matches involved and whatever the number of packet sections.

The match combs 10 are stored in pairs 11, one pair above another in a hopper 12, each pair including combs 13 and 14 having their stick ends reversely turned, those in the lower comb of the pair pointing forwardly, in the correct direction.

The hopper rests at position A above a table 15 upon which the combs are ejected to position B by a plunger unit 16 including a plunger 17 and operating mechanism seen in Figure 6. From this position the upper combs are flipped a half turn each about a transverse axis and are also transferred from conveyor position B to conveyor position C, by a unit 18 (Figures 1 and 6) including flipper 19.

The table is slotted longitudinally throughout most of its working length at 20, 21, 22 and 23 to permit operation in these slots of a plurality of 45 conveyor flights 24, 25, 26 and 27 carrying pusher conveyor blades 28, 29, 30 and 31 and, along with the cradle conveyor operating mechanism for it (Figures 2, 4 and 5), forming a pusher conveyor unit 32.

50 At a suitable position to the left of the flipper unit is located a cutting unit 33 comprising cutting knives 34 to cut off the side sections and knives 35 to cut the center, as well as the operating mechanism for these knives.

55 At the left end of Figure 3 and at the left in

Figure 4 is shown a transverse conveyor, indicated as of chain type, having successive groups of chains and corresponding comb-section-supporting devices 36 in the form of spring clips 37.

All of the mechanism is illustrated as being driven from a main shaft 38 mounted upon a standard 39 and communicating by pulley 40 and belt 41 with a pulley 42 upon an intermediate or countershaft 43. Upon the countershaft is mounted a pulley 44 connected by belt 41' with a pulley 45 mounted upon a third shaft (second countershaft) 46. Any suitable motor or belt drive (not shown) may be applied to shaft 38.

A plunger 17 is guided to move through openings 47, 48 in the front and back of the lower part of the hopper. It is important that the pusher eject a pair of combs (an upper comb and a lower comb of the same pair, together) each time and this is ensured by providing prongs 49 at intervals along the upper pusher edge, which fit into the spaces between the matches of the lower comb pair and the heads of the lower comb in the next upper pair of combs.

The plunger is thrown to the left and back again by a link 50, engaging pivotally with the plunger at 51 at one end and at the other end at 52 with the longer end 53 of a lever 54. The lever is pivoted at 55 in a bracket 56 carried by the bed.

The lever extends beyond the pivot 55 at 57 and terminates in a roller 58 which lies within a cam slot 59 opening from the face opposite to the observer in Figure 6 of an internal cam wheel 60 driven by the second countershaft 46.

The lever extension 57 (the shorter arm of lever 53) is of such proportion and the internal cam slot is of such throw and angular location with respect to the conveyor movements that the plunger operates at every other conveyor stage of movement, after the conveyor starts to move. This is secured by the angular timing of the cam slot and by rotation of the cam wheel 60 but once for each two stages of movement of the conveyor.

Each lower comb of a pair is shifted from position A to position B before another pair of combs can be ejected. A second set of flight conveyor blades follows the ejected pair into position to be ready to transfer the lower comb of each pair to position C in the next (second) conveyor stage movement.

At the same time that the first stage of flight conveyor movement is shifting the flight conveyor blades which had been back of position B to a position where they are back of position C, other flight blades have transferred a comb from position C to position D. This clears position C.

That position C shall be clear at this time is necessary for two reasons: (1) so that the flippers can emerge from their dotted position in Figure 1 to make a clockwise half turn and come back again and (2) so that on the back stroke of the flippers there will be an empty position C upon which to rest the comb which is flipped.

It will be clear that the flippers engage, advance and turn over end for end the upper comb only of each pair so that the combs are then arranged with the same match ends forward in all positions throughout the conveyor length.

The flipper movement must take place during the interval between the first conveyor flight movement and the beginning of the second conveyor flight movement, for the reason that the position C is not vacant for operation of the flipper until after the first conveyor flight movement and the second conveyor flight movement, if it began, would move the comb pair (or the lower one of

the combs if the flipper had raised the upper one) from position B so as to interfere with the flipper deposit of the upper one of the combs upon position C.

5 There are two flippers, one extending into the bed position from one side and the other from the other side. Except for the differences necessary because of the direction of extension, they are identical. For this reason the one nearer to the observer in Figure 1 only will be described.

The flipper normally lies in the position seen in Figure 1 in dotted lines with the nozzle mouth below the surface of the bed and from that position turns in clockwise direction 180° and back again through an opening 61 in the table.

The flipper supply pipe tube 62 is mounted in bearings 68 and 69, preferably using filler 70 as the inner bearing member, and preventing longitudinal pipe movement by a flange 72 upon a filler engaging one bearing.

Each flipper includes an oscillatory supply pipe tube 62, terminating in an externally threaded flange 62' and a transverse closure plate 62² having an opening in half of the plate, performing air valve functions (see Figures 2^a and 2^b). The pipe connects with a nipple 63 (Figure 2) from which vacuum connection is made. The nipple end also carries valve plate 63' having opening 63² in half of the plate.

30 The two openings 62³ and 63² register in the position of Figure 1 to apply vacuum or to cut off air suction according to the position of the flipper, seen at the left in dotted lines in Figure 1. Vacuum connection is applied at intermediate positions. Flange 63' upon the outer circumference at the end of the nipple is engaged by interior flange 64' within nut 64. Internally threaded sleeve 64² on this nut engages threaded flange 62' to hold the parts together.

40 At the opposite end of the oscillatory pipe from the nipple is located an off-center open mouthed flipper nozzle 65. The nozzle is connected with the tube through an elbow 66 and an off-center nearly radial tube section 67.

45 A gear wheel 73 is mounted to rotate with the pipe. Its hub 74 can be used to limit suction pipe movement by engagement with the bearings. The flipper nozzle mouth normally lies a little below the table and oscillates between that position and the position shown by line 75 representing the height of the pair of combs ejected (see Figure 6). Suitable valve mechanism operates during counterclockwise movement of the flipper from a position at which the flipper's mouth engages the top comb until the flipper deposits this upper comb at position C. This valve construction is not intended to be claimed by me in this case. A sleeve valve opened by movement of the flipper or separate valve mechanism might be used.

50 60 Gear 73 is turned by gear 76 upon bearing 77, and is rocked by thrust rod 78 turning about a pin 79. A quadrant stroke is provided, between pin position 80 and pin position 81. Since gear 76 is position 80 and pin position 81. Since gear 76 is twice the diameter of gear 73, gear 73 is thus oscillated through 180° of turning movement.

65 Thrust rod 78 carries wheel 82 which fits into face cam 83 of cam wheel 84 carried by shaft 46. Cam wheel 84 rotates of course at the same speed as cam wheel 60, i. e. one turn for every two stages of flight conveyor as above.

70 75 The angular position and extent of the internal cam used to operate thrust rod 78 and the position of this thrust rod must be such that the thrust rod suitably guided will lift and lower to

give a complete oscillation of the flipper immediately after the new pair of match combs is ejected, so as to engage the top of the pair with suction in the extreme clockwise position of the flipper and to return the flipper to its normal position, still with suction "on," depositing the upper match comb at position C (releasing the suction) in time for this upper match comb to be transferred from position C to position D at the next (second) stage of movement of the conveyor flights.

Figures 1 and 3 are intended to provide positions and operating mechanism for handling the match combs, and the sections cut from them, from the hopper to their final delivery between the spring clamping clips carried by the links of the chain conveyor.

Figure 1 includes the hopper (position A); the ejecting mechanism delivering to position B; the flipping mechanism turning between positions B and C at which latter the flipped combs are delivered at the end of the return flipper stroke; and positions D and E and a part of position F.

Though the flipping is over at position C and it will be possible to begin cutting at position D, so far as the actual freedom from interference of mechanisms is concerned, non-active positions are provided, such as D, E and F which may vary in number according to the length of space desired, in which there is opportunity for placing combs if any of the combs fail to be fed by the plunger and flipper in the preceding positions. This avoids gaps in comb sections fed to the clips carried by links in the chain conveyor.

The combs which have been fed from the hopper are fed through these relatively idle spaces or positions but no operation is intended to be performed upon them at these idle points.

The further operation of the mechanism comprises the handling of the match combs to cut them up into match packet sections and to space them laterally so that they may properly register with clip receiving devices carried by a chain conveyor, one clip and one packet section for each link of the length of the chain conveyor.

The match combs considered are described for a group of four match packet sections each and the operation based upon such comb length is described herein, but this is by way of illustration only. The combs are advanced step-by-step to the position at which the first cuts are to be made. The first cuts take off the match packet sections at the ends, leaving the center pair of match packet sections still united. As soon as the match packets at the ends have been cut free (at position G), they are diverted to space them from the central (as yet uncut) pair of match packet sections before the latter shall have been cut free. This gives time so that there shall be time to divert the outside match packet sections additionally when the match packet sections comprising the central pair are divided at a later position (at position H) and as the central sections are separated, one from the other of each pair. In order that this may be accomplished, the cutting operations, first that of cutting off the two side sections and next that of dividing the sections remaining, are spaced along the conveyor length to any convenient extent but it is not necessary to space the cuts farther longitudinally of the comb travel than one packet position because that spacing is sufficient so that the outside sections can be diverted before the second cut is made, by which second cut the inside sections are separated and can be diverted.

It will be evident that the side and central cuts are made concurrently and the central knife is located in advance of the others, cutting in a laterally central portion upon a match comb which already has had its side portions trimmed from it and which moreover has had its side match sections diverted from the central section.

In Figure 3 the first position is shown. It is or may be an idler position, such as F, seen in part in Figure 1, but the first action takes place in position G and further operating positions are shown at H, I, J and K.

The flight conveyor is used to carry the match combs, after they have been cut off the match comb sections. This conveyor will be described next.

There are four conveyor flights, two acting from the hopper to the chain conveyor and two acting from some such position as F to the chain conveyor. Each of the conveyor flights occupies a separate position laterally of the table and moves in a corresponding longitudinal slot separate and distinct from each other conveyor flight and slot, except that they are all operated by one common supporting, lifting and oscillating mechanism. Each moves its blades and the combs or comb sections in front of them through one position length and then returns to move succeeding combs or comb sections through the same position length.

The conveyor flights are nearly identical, differing in that the two flights near the middle of the table are extended farther than the two flights adjacent the respective outer edges of the table.

There are three reasons for this. One is that the two flights near the middle of the width of the table are sufficient to handle the match combs until after they are cut, and so are used beginning at position B to advance the lower comb of the pair ejected to the left from position B to position C, to advance the combs at C to D, D to E, E to F and F to G. Another reason is that the positions of the flippers interfere with operation of the outside conveyor flights beyond position F or position E. A third reason is that the cutting of the sections from the combs begins at the outer ends of the comb and these outside conveyor flights have their first separate duty when the first cuts have been made, which in Figure 3 is seen to be at position G.

Another feature in which the four flights are not all alike is that though some pusher blades in each of the flights are laterally offset with respect to other pusher blades in the same flights, pusher blades in the outer flights are farther offset within the total lengths than are the pusher blades for the inner flights because the outer flights must take care of not only their own spacing from the inner flights but the ultimate spacing of some of the pusher blades of the inner flights, one flight from the other.

The mechanism by which the flight conveyors are operated in unison is shown in Figures 1, 3, 4 and 5.

Tubular guides 85 for the conveyor driving mechanism are carried by pedestals 86 on opposite sides of the table. Within the guides 85 move vertical rods 87 rigidly connected with the side bars 88 of a cradle 89, in which bars reduced ends 91, 91 of the rods are held by nuts 92. The side bars carry guides 93 for a blade-supporting plate 94.

The cradle is lifted and lowered by mechanism best seen in Figures 4 and 5.

The height of the plate is thus determined by the mechanism of Figures 4 and 5 and it is shifted

forwardly and rearwardly by the arm 109. The extent of movement is short, and a match comb or match packet which has been shifted by one conveyor blade is engaged by the next conveyor blades progressively to carry it from one end of the conveyor to the other and finally to engage the strips at the stick ends of the matches with the clips of the chain conveyor as later described. The composite movements effected by the lifting, and longitudinal shifting, of the plate result in the conveyor blades from their forward positions lowering beneath the table, travelling rearwardly in the lower position, lifting at their limits of travel and moving forwardly in their lifted position to perform their conveying functions.

Countershaft 43 carries two lifting face cams 95 and 96 and an intermediate face cam 97 by which oscillation of the plate 94 is secured. The lifting face cams have facing cam grooves 98 and 99 which receive rollers 100 secured by pins 101 upon thrust arms 102, 103. The thrust arms connect at their upper ends through eyes 104, 105 and pins 106 with the side bars 88. At the lower ends these thrust arms are divided to form yokes at 107. These yokes straddle guides 108 rotatable with the shaft, maintaining the lower ends of the thrust arms against movement transversely of the countershaft. The face cams, rollers and thrust rods thus provide vertical movement of the cradle side bars and of the plate 94.

The lever arm 109 is pivoted at its lower end at 110 about a fixed pin 111 and at its upper end is pivotally connected to link 112 which connects at the opposite end to pin 113 in eye 113 rigid with the plate 94. At an intermediate point the lever arm 109 carries roller 114 by pin 115. The roller and its lever are shifted laterally by the walls of a cam groove 116 in a face cam 97 rotatable with the countershaft.

The two face cams 95, 96 with their thrust rods and the face cam 97 with its oscillating arm are timed to produce a composite movement of the plate 94 and of the pusher flight conveyor blades (for all of the flight conveyors) such that the blades travel to the left in Figures 1 and 3 during their match comb and match comb section conveying movement, lower at the extreme left so that the blades drop below the table level, travel to the right in these figures in their inactive return movement, and finally lift at the extreme right so that the blades reach above the table and are in position to carry match combs and match comb sections with them on their next conveying movement to the left. The composite movements of all of the blades of all of the flight conveyors are therefore the same and are timed the same so that when the lower match comb of the ejected pair is being moved from position B to position C, match combs or later match comb sections are being moved by other blades from position C to position D and from position D to position E, etc. throughout the length of the table, the final blades at the left of the figures forcing the match combs between spring finger clips attached to and carried by links of the link belt conveyor.

The upper ends of the rods 87 are extended to carry a beam 117 held to them by nuts 118, 119. The beam supports knives 34—34 (Figure 5) intended to operate lengthwise of the bed at position G in the drawing in Figure 3, and a knife 35 intended to operate also longitudinally of the bed at position H in Figure 3. These knives are supported from the beam by brackets 120. The knives lift and lower with the conveyor cradle and hence perform their cutting functions at the

same time that the flight conveyor blades drop below the surface of the table ready for their return movement to the right in Figures 1 and 3. They therefore cut after the flight conveyor blades have carried match combs or match comb sections to the respective positions G and H and while the combs at position G and comb sections at position H are resting free from movement.

The conveyor blades 28—31 are supported from the plate 94 by brackets 121 to which they are held by means of bolts 122.

The cutting knives have each a length along the length of the bed just sufficient reliably to cut the stubs of the match comb material to separate parts of the comb into comb sections, at position G, to cut off the outer comb sections from the two as yet integral intermediate comb sections which in turn are divided at position H.

In Figure 1 the entire lengths of the table slot portions seen are straight, that is parallel with the length of the table and without offsetting. The two flights 25 and 26 only are extended to engage combs at position B and these flights are the only ones whose blades transfer from position B to position C, from C to D, from D to E and from E to F.

At position F the blades of flights 24 and 27 come into operation, preliminary to the separation of the outside sections of the match combs from the intermediate sections. Until this separation takes place at position G the intermediate flights 25 and 26 are sufficient to handle the match combs. Since the slots for the outside flights are not cut through beyond position E, the table can be supported additionally to the right of position F by a generally triangular frame reinforcement 121 which stops at the slots 21 and 22.

The movement of the flight conveyors and the coincident movements of the cutting knives set the time of the entire mechanism. Though the slots and conveyor blade positions are in line up to position G, where the first cuts take place, from position G on the comb sections are diverted laterally as well as conveyed lengthwise of the table; and the flight conveyor blades contribute to the diversion or separation of these comb sections. This is readily accommodated because the conveyor blades move only the length of one position and then reverse their direction. This affects flights 24 and 27 from G to H and all of the flights from H to I, from I to J and from J to K.

The diversion beginning at position G after the cuts have been made at that point, are effected, by a combination of guides, and offsetting and sloping pusher faces. The diagonal guiding members 123 and 124 extend between slots 20 and 21 and between slots 22 and 23 from the left ends of position G to the right ends of position J, respectively beyond which, with the construction shown, they are not needed, and diagonal guide faces 125 and 126, are effective between slots 21 and 22 from the left end of position H to position J.

The transfer blades are offset successively in the outer flights at positions H, I and J with respect to the placing of these parts in position B to G, and in the inner flights they are offset at I only. There is a corresponding offsetting of the slots within which these blades travel.

Since the outside sections only have been severed at position G, from this position to position H these are the only sections which are diverted and the blades which transfer from position G

to position H, therefore divert only as to blades 28 and 31 of flights 24 and 27. However at position H, where the cut takes place between the two intermediate match comb sections, these intermediate sections are also diverged and because of their divergence the outer sections must be further diverged to make room for them. For this reason all of the blades 28, 29, 30 and 31 are offset for transfer from position I to position J and the blades 28 and 31 are offset for transfer also from position J to position K.

The diagonal guides 123 and 124 as well as the diagonal guide faces 125 and 126 are assisted in their guiding function by diagonal front faces 127 of the blades 28 and 31 at position G for transfer from position G to position H; and as to all the blades from position H to I and from position J to position K.

The diversion of the sections separates them to the intended extent during their transfer from position to position until as they rest at position J they are separated each from its adjoining sections by the distance desired in operating upon them subsequently; and with this spacing the final conveyor blades transfer the sections from position J to position K at which their respective stubs are pushed between the springs of clips 37 carried by the successive links of the chain conveyor unit 36.

In order to show utility for the separating and spacing of the comb sections into four concurrently fed comb sections—or permissibly a different number, where the intended group is different—the chain conveyor mechanism is described by which mechanism the sections forming the selected group are received by the chain conveyor and are transferred to another position, or to other positions for further operations.

The construction by which the chain conveyor is advanced is shown at the left in Figure 4. Upon the main shaft 38 is mounted a worm 129 which engages successively with rollers 130 upon a gear 131. The worm and roller spacing ensures that the worm is always pressing against at least one roller.

Gear 131 meshes with a gear 132 mounted upon a shaft 133 which carries also a sprocket or gear wheel 134 by which chain 135 of the chain conveyor is driven. This chain conveyor carries spring clips 37, one for each link. The gears 131 and 132 are supported from a bracket 136 and the worm (cam) and gear connection (ratio) is such that the rollers upon gear 131 are advanced one roller for every conveyor position feed; but this distance is multiplied because of the ratio of gear 131 to gear 132 so that for each one position advance of the first (flight) conveyors (carrying four sections) the transverse (chain) conveyor advances four clips at a time. These receive the four sections of comb and, with the next step-by-step conveyor advance, pass on while four other clips take their places. In other words, four chain conveyor links with their spring clips are advanced at a time and are maintained in position to receive four match comb sections for each feed of the flight conveyors.

The chain conveyor advances the clip-supported match sections, in groups of four to successive positions perpendicular to the paper in Figure 4 and holds the sections while they are acted upon to apply wraps and covers and thus to form packets. The movements of the chain conveyor take place during times when the flight conveyors are not moving the sections and per-

missibly while the flight conveyor blades are depressed beneath the table for their idle return movements.

5 The combs are advanced step-by-step by the flight conveyor and at suitable stops the sections intended for match packets are cut apart and the match packets are separated to a distance corresponding to that at which they are to be acted upon in further operations.

10 In the mechanism shown, in which the full comb is divided into four quarter comb sections, it has been convenient to cut the outside sections off first, in position G, and to separate the two inside sections from each other later as at position H.

15 After the separation of the outside sections at position G, the conveyor flights perform a combined function upon these sections, namely pushing them forward and at the same time guiding them diagonally to a proper spacing from the as yet unsevered middle portion of the comb. The two inner sections are then separated and the flights of the conveyor push them forward and at the same time divert them to give their proper spacing. Concurrently the outside sections are 20 further diverted to maintain proper spacing between them and the now diverging inner sections.

25 When the four sections have been properly spaced and positioned they are pushed sticks first into the four clips of the (transverse) chain conveyor.

30 Since each step-by-step movement of the four flight conveyors place four match sections to the chain conveyor, the chain conveyor match receiving clips advance in units of four clips at a time to receive them, carrying them off to the left in the figures in time for four new clips to replace the four just filled so as to receive the next group of four sections fed by the flight conveyor.

35 40 In view of my invention and disclosure variations and modifications to meet individual whims or particular need will doubtless become evident to others skilled in the art, to obtain all or part 45 of the benefits of my invention without copying the structure shown, and I, therefore, claim all such in so far as they fall within the reasonable spirit and scope of my claims.

Having thus described my invention what I 50 claim as new and desire to secure by Letters Patent is:

55 1. In a match comb handling system, a table, a step-by-step flight conveyor movable therein and having a plurality of conveyor blades, a cradle supporting the conveyor blades and in which the conveyor blades are movable longitudinally of the table, cam operated means for lifting and lowering the cradle and cam operated reciprocating means guided by the cradle moving the conveyor blades longitudinally of the table, means for timing the several cam operated means to lift the conveyor blades to operating height above the table, to move the conveyor blades lengthwise of the table while they carry the match combs one 60 step, to lower the blades below the table level and to reverse the blade movement beneath the table to a position where the blades can be raised, moved, lowered, reversed, etc, to repeat the operation.

65 70 2. In a match comb handling mechanism, a step-by-step flight conveyor having blades in sets oppositely offset with respect to each other in a general direction of travel and forwardly directed diagonal faces upon the offset blades, the diagonal faces being disposed oppositely, whereby 75

sections of match combs which are laterally spaced with respect to the direction of travel are engaged by the different blades and the diagonal faces tend to further separate the said sections laterally.

3. In match comb handling mechanism, a conveyor system comprising a plurality of conveyors which are positioned in spaced lateral arrangement and move in step-by-step motion, each conveyor comprising a plurality of longitudinally spaced flights made up of blades, some of which are offset from one another at their different step-by-step positions, means for forwardly advancing the conveyors in the step-by-step movement, cutting mechanism for separating the match combs, adapted to cut transversely of the combs and located in position laterally between the flights of the conveyors, whereby the combs are cut into comb sections adapted separately to be conveyed by the flight conveyor, guiding mechanism within the path of movement of the comb sections for diverting match comb sections cut from other comb sections and tapered faces on the offset flight blades tapering in a diagonal direction in which the comb sections are guided.

4. In a match comb handling mechanism, a plurality of conveyor flights each having a plurality of blades, some offset with respect to others in each of the flights, cutting mechanism for cutting outer match comb sections from inner match comb sections at one step-by-step conveyor position, cutting means for cutting the inner match comb sections from the match comb at a later conveyor position as compared with the first cutting means, and guides for diverting the match comb sections after they have been cut, the blade positions being offset to accommodate the sections in the positions to which they have been guided.

5. In a match comb and comb section handling system, a table having longitudinal slots, having narrower spacing, slot to slot at the rear ends of said slots than at their forward ends, flights operating in said slots, having forward faces inclined at an angle to the directions of movement of said flights, for engaging comb sections to divert said sections from the line of slots of narrower spacing to the line of slots of wider spacing and means for raising and lowering and for reciprocating the flights to move the match comb sections toward the positions of wider slot spacing.

6. In a match comb and comb section handling system, a table having longitudinal diverging slots, having wider spacing, slot to slot at the forward ends of said slots than at their rearward ends, flights operating in said slots and fixed guides between said flights and diverging at an angle to the directions of movement of said flights, tending to divert comb sections from the line of slots of narrower spacing to the line of slots of wider spacing and means for raising and lowering and for reciprocating the flights to move the match comb sections toward the positions of wider slot spacing.

7. In a match comb and comb section handling system, a table having longitudinal slots progressively at wider spacing one slot from the next, conveyor flights progressively at wider spacing, one slot from the next, adapted to engage successive match combs or comb sections in each of said slots, means for advancing said flights in engaging position, for lowering the flights from engagement with the combs or sections, for reversing the movement of said flights in idle

movement, and for lifting said flights to cause the flights to engage comb sections for reengagement but with other match comb sections, knives adapted to separate the match combs into match comb sections and operated by the means for lowering and lifting the flights, there being slots extending parallel to the direction of advance in advance of the first slots, generally in line with them but having wider spacing between the slots than the spacing of the first slots, additional flights operating in the more widely spaced slots, the conveyor flights including outwardly wedging, forwardly pressing movable means for diverting the match comb sections cut, from the lines of the first slots to the lines of the second slots, respectively, as the sections cut are advanced by the several flights.

8. In a match comb and comb section handling system, a table having longitudinal slots progressively at wider spacing one slot from the next, conveyor flights progressively at wider spacing, one slot from the next, adapted to engage successive match combs or comb sections in each of said slots, means for advancing said flights in engaging position, for lowering the flights from engagement with the combs or sections, for reversing the movement of said flights in idle movement, and for lifting said flights for re-engagement but with other match comb sections, knives adapted to separate the match combs into match comb sections and operated by the means for lowering and lifting the flights, there being slots extending parallel to the direction of advance in advance of the first slots, generally in line with them but having wider spacing between the slots than the spacing of the first slots, additional flights operating in the more widely spaced slots and operated by the same means as the first flights, the conveyor flights including outwardly wedging movable means for diverting the match comb sections cut, from the lines of the first slots to the lines of the second slots as the sections cut are advanced by the several flights.

9. In a conveyor for match sections, a conveyor bed having longitudinally extending spaced rear slots and forward slots in general line with them but ahead of them and spaced a wider distance than the spacing of the rear slots, conveyor flights located in the several slots, advancing and retracting means common to the flights for bringing the flights into engagement concurrently with various match sections so as to shove the match sections forwardly when the flights are in raised position and to retract the flights in reverse direction when the flights are in lowered position and means for concurrently lifting the flights prior to their forward movement so that the flights will engage with the match sections and for concurrently lowering the flights when they have reached the forward end of their flight stroke in order that they may be idled back.

10. In a conveyor for match combs and match sections, a conveyor bed having longitudinally extending spaced rear slots and forward slots in general line with them but ahead of them and spaced a wider distance than the spacing of the rear slots, conveyor flights located in the several slots, means common to the flights for advancing the flights in raised position concurrently to push match sections lengthwise of the bed to the end of the forward flight stroke and, after the flights are lowered, to idle the flights reversely to the rear position of their stroke, means for concurrently lowering the flights at the end of their forward strokes and for concurrently lifting the

flights at the ends of their rearward strokes into their initial positions, to engage with a new set of match sections for the next movement, and forwardly and outwardly sloping faces upon some of the flights to press sections outwardly with forward movements of the flights so that the sections are in line for engagement at the next flight movements by more widely spaced flights.

11. In a conveyor for match sections, a conveyor bed having longitudinally extending spaced rear slots and forward slots in general line with them but ahead of them and spaced a wider distance than the spacing of the rear slots, conveyor flights located in the several slots, means common to the flights for advancing and retracting the flights longitudinally with respect to the slots, means for lifting the flights prior to their forward movement along the slots and for lowering the flights after this forward movement has been completed, cutting means acting concurrently at different positions along the lengths of the slot to cut match combs located at different distances along the lengths of the slots, mechanism for operating the cutting means, and means for diverging the match combs cut at the different positions whereby the match comb sections ultimately cut are spaced uniformly from each other.

12. In a conveyor for match sections, a conveyor bed having longitudinally extending spaced rear slots and forward slots in general line with them but ahead of them and spaced a wider distance than the spacing of the rear slots, conveyor flights located in the several slots, means common to the flights for advancing and re-

tracting the flights longitudinally with respect to the slots, means for lifting the flights prior to their forward movement along the slots and for lowering the flights after this forward movement has been completed, cutting means acting concurrently at different positions along the lengths of the slot to cut match combs located at different distances along the lengths of the slots, mechanism for operating the cutting means, there being conveyor-flight-carried diverging guide surfaces engaging the match sections during their forward travel whereby the sections are shifted into position to be engaged by the more widely spaced flights and guide means for diverging the match combs cut at the different positions whereby the match comb sections ultimately cut are spaced uniformly from each other.

RODNEY S. PULLEN.
